TABLE SKITTLE ALLEY

Heinrich Freytag, Neuenkirchen Kreis Soltau
Hann. Soltau-Land, GermanyApplication July 8, 1932, Serial No. 621,386
In Germany July 13, 1931

2 Claims. (Cl. 273—38)

This invention relates to a skittle alley which is of such dimensions that it can be placed on a table or the like.

The skittle game is provided with a ball track 5 adapted to be brought into different angles of inclination and oscillated in its longitudinal axis. On the track which can be used on both sides, a projecting device with handle is provided, which handle at the same time enables a slight turning of the track whilst the ball is running thereon. The projected ball rolls towards a skittle supporting plate, the skittles of which can be set up by a common pull device. For this purpose the skittles are connected to cords having tension springs at a portion of their length. These tension springs are connected to a connecting element, which in turn is connected to a further spring attached at one end to the base of the alley and determines the initial position of a common pull cord.

An embodiment of the invention is illustrated by way of example in the accompanying drawing in which:—

Fig. 1 shows the complete alley in longitudinal section.

Fig. 2 is a top plan view of Fig. 1.

Fig. 3 shows in top plan view the tension springs with connecting element and the common pull cord.

Fig. 4 is a detail sectional view taken on line 4—4 of Fig. 2.

The base 1 carrying the entire equipment of the game is surrounded by an edge 2 of sufficient height to prevent the loss of the ball. The board 3 carrying the skittles 3' rests on a box 4 which protects the cords 3'' of the skittles 3' against detrimental external influences. A track 5 carrying a projecting device 6' provided with handle 6 is hingedly suspended by means of two pins 5' and 5''. The pin 5'' is further exchangeably inserted in holes 7 arranged at different heights in an upright plate 8 foldable on a hinge 8'. It is possible to adjust the inclination of the track 5 by means of the arrangements of the holes 7 at different heights. The upright plate 8 is mounted on the hinge 8' so that it can be folded down, as already mentioned,

for facilitating transport. The ball, which is guided on to the track 5 by raising the projecting device made in circular shape, rolls down this track and can be influenced by turning the track 5 with the aid of the handle 6. After knocking against the skittles 3' the ball rolls on to the base 1 and runs back to its initial position where it remains easily accessible in a ball catcher 9.

The skittles are set up by cords 3''' which are connected by means of tension springs 10 and a connecting element 10' to a pull cord 11 provided with a handle 11' to facilitate its operation. The element 10' also carries an additional spring 10'' which is connected to the base 1 and serves for bringing the pull cord 11 into its initial position. The track 5 has a groove-shaped running surface 5a as shown in Fig. 4 whereas the opposite surface is flat. This enables the track to be employed in two different ways; firstly the ball can be allowed to run on a flat track and secondly, by merely turning over the track bar 5, the grooved construction can be employed.

While there is herein shown and described the preferred embodiment of the invention, it is to be understood that minor changes may be made therein, such as will fall within the scope of the allowed claims.

I claim:—

1. On a table skittle alley with arrangement for setting up the skittles a ball track oscillatable about its longitudinal axis, a curved ball projecting strap adapted to the shape of the balls rotatably mounted on said track perpendicularly to the longitudinal direction thereof, and lateral handles on said strap adapted to turn said strap and hold said track.

2. On a table skittle alley with arrangement for setting up the skittles, a ball track oscillatable about its longitudinal axis and having curved cross sectional shape towards the center thereof, a curved ball projecting strap adapted to the shape of the balls rotatably mounted on said track perpendicularly to the longitudinal direction thereof, and lateral handles on said strap adapted to turn said strap and hold said track.

HEINRICH FREYTAG.
